UNITED STATES PATENT OFFICE.

ROBERT J. BARKLEY, OF CHANUTE, KANSAS.

DESIGN FOR AN EGG-CARTON FILLER.

SPECIFICATION forming part of Design No. 30,088, dated January 31, 1899.

Application filed November 25, 1898. Serial No. 697,460. Term of patent 14 years.

To all whom it may concern:

Be it known that I, ROBERT J. BARKLEY, a citizen of the United States, residing at Chanute, in the county of Neosho and State of Kansas, have invented and produced a new and original Design for Egg-Carton Fillers, of which the following is a specification, reference being had to the accompanying drawing, forming a part thereof.

10 This design relates to fillers for egg-cartons, by which means cells are formed in the cartons, so as to receive individually the eggs, thus preventing them from contacting with each other and avoiding the fracture of the 15 eggs.

The drawing represents a perspective view of an egg-carton filler illustrating my design.

The design presents prominently a single central longitudinal member *a* and a series 20 of transverse members *b*, the member *a* bisecting the members *b* and the said members *b* having their outer ends projecting as free wings at each side of the member *a*, the whole 25 presenting two parallel series of equal three-sided rectangular figures open at their outer sides.

In detail the longitudinal member *a* is continuous through the several transverse mem-

bers *b*. In the member *a* slits *a*² appear, one near each end and running upward from the 30 lower edge, while from the opposite or upper edge slits *a'* appear, running downward at regular intervals, as shown, thus leaving a lower edge of unbroken continuity between the slits *a*², while the upper edge appears 35 broken at intervals corresponding to the positions of the members *b*, except at the end members *b*, where the upper edge continues unbroken.

The leading feature of my design consists 40 in the carton-filler presenting two parallel lines of three-sided figures, the open end being at the outer sides of the filler and the whole being formed of a single central longitudinal member *a* and the transverse members *b*, the member *a* bisecting the members *b* and presenting in plan view the appearance 45 of a single linear member running continuously through the center of the filler.

I claim—

50 The design for an egg-carton filler herein shown and described.

ROBERT J. BARKLEY.
